APPARATUS FOR ANCHORING TUBING STRINGS
IN WELL BORE CONDUITS

Reuben C. Baker, Coalinga, Calif., assignor to Baker Oil Tools, Inc., Los Angeles, Calif., a corporation of California

Application April 2, 1954, Serial No. 420,527

10 Claims. (Cl. 166—212)

The present invention relates to subsurface well tools, 15 and more particularly to apparatus for anchoring strings of tubing, and the like, to well casing and similar conduits disposed in well bores.

An object of the present invention is to provide an improved subsurface well tool capable of anchoring a string 20 of tubing in a well casing against longitudinal displacement, the tool being capable of safely withstanding comparatively high pressures.

Another object of the invention is to provide a hydraulically actuatable tubing anchor operable by pressure 25 differentials internally of the tool to move and hold the anchoring members against the well casing, in which the tubing anchor embodies devices for equalizing internal and external pressures, if necessary, in order to obtain release of the tool from the well casing, in the event such pressures are not otherwise equalized.

A further object of the invention is to provide a tubing anchor having gripping members that are expanded outwardly into engagement with a well casing by hydraulic pressure within the tool, in which any pressures below the 30 tool and tending to elevate it are utilized to engage the gripping members more securely against the well casing.

Yet a further object of the invention is to provide a tubing anchor having gripping members expanded outwardly into engagement with a well casing by hydraulic pressure within the tool, in which release of the gripping members can be assisted by imposing a downward force 40 on the tool in the well casing.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is 50 to be understood that such detailed description is not to be taken in a limiting sense, since the scope of the invention is best defined by the appended claims.

Referring to the drawings:

Figure 1 is a combined longitudinal sectional and side 55 elevational view of an embodiment of the invention, with its gripping members in retracted position, to enable the tool to be moved longitudinally in a well casing;

Fig. 2 is a view similar to Fig. 1, disclosing the equalizer valve in open position;

Fig. 3 is a view similar to Fig. 1, disclosing the tubing anchor anchored against the well casing;

Fig. 4 is a fragmentary enlarged longitudinal section 60 of a portion of the equalizer valve.

As disclosed in the drawings, a tubing anchor A is to be lowered through a string of well casing B by means of a string of tubing or drill pipe C to a point in the casing at which it is to be anchored therewithin. The tubing anchor may be connected with another tool (not shown) secured to its lower end. As an example, this undisclosed tool may consist of a well packer adapted to en-

2

gage the well casing in packed-off condition and resist downward movement therewithin.

The tubing anchor A includes an upper tubular mandrel or inner member 10 adapted to be threadedly attached to the lower end of the tubing string C. This tubular mandrel is telescopically arranged within a tubular body 11 formed of several sections. Thus, the main intermediate portion 12 of the tubular body has its lower end threaded onto a lower body member 13, which may have a lower threaded box 14 for attachment to tubing or to a tool (not shown) therebelow. The upper portion of the body 11 is threaded onto a cap or lock ring 15 slidably engageable with the exterior of the tubular mandrel 10. To prevent foreign matter from passing between the body 11 and mandrel 10, a suitable rubber wiper ring 16 may be secured to the cap 15 for slidable sealing engagement with the mandrel 10.

Disposed around the body 11 in circumferentially spaced relation are a plurality of longitudinal slots 17 in which gripping members 18 are slidable. The sides of the gripping members slidably engage the sides of the slots 17, the gripping members encompassing a rubber, or rubber-like, expansion sleeve 19, whose upper and lower ends engage the interior of the intermediate body member 12 on opposite sides of the slots. The lower portion of the expansion sleeve 19 is disposed within an annular space between the upper portion 20 of the lower body member 13 and the intermediate body member 12 below the slots 17. The upper end of the rubber sleeve 19 is disposed within a companion annular space formed between the intermediate body member 12 and an outwardly directed flange portion 21 of an inner protective nipple 22, which depends from the flange portion along the inner surface of the rubber sleeve 19, and whose lower end engages a shoulder 23 on the lower body member 13. This nipple or protective member 22 has a plurality of side ports 24 establishing communication between the interior of the nipple 22 and the interior of the rubber expanding sleeve 19. The inner nipple 22 is held in a downward position in snug engagement with the shoulder 23 by a clamp nut 25 threaded into a threaded box portion 40 in the upper end of the intermediate body member 12 and engaging the upper end of the nipple. This nut 25 is prevented from loosening by a suitable set or lock screw 26 threaded through the body wall and engaging the clamp nut.

Leakage of fluid around the upper end 19a of the expansion sleeve is prevented by forming it as a lip or edge adapted to engage the inner wall of the intermediate body member 12. Similarly, leakage of fluid around the lower end 19b of the expansion sleeve is prevented by forming it as a lower lip seal engaging the inner wall of the intermediate body member 12. Fluid under pressure between the expansion sleeve 19 and the nipple 22 will press these upper and lower lip seals 19a, 19b securely against the inner wall of the intermediate body member 12, and prevent such fluid from passing around the sleeve to its exterior. Leakage of fluid endwise from the expansion sleeve 19 is further prevented by a suitable upper side seal ring 27, such as an O ring made of rubber or rubber-like material, contained within a groove 28 in the upper portion of the nipple and engaging the inner wall of the intermediate body member 12. Similarly, leakage of fluid through the threaded joint between the intermediate body member 12 and lower body member 13 is prevented by a rubber or rubber-like O ring 29, or corresponding side seal, contained within a groove 30 in the lower body member 13 and engaging the inner wall of the intermediate body member 12 below the lower lip 19b. It is evident that the lip seals 19a, 19b and the side seals 27, 29 prevent fluid from passing out of the interior of

3
the rubber expansion sleeve 19 except through the nipple ports 24.

Fluid under pressure within the tubular mandrel 10 and the nipple 22 exerts an outward expanding force on the rubber expansion sleeve 19, carrying the gripping members 18 outwardly to embed their external portions 18a, which may be provided with suitable wickers or teeth, outwardly into anchoring engagement with the wall of the well casing B. When the internal pressure is relieved or substantially equalized with respect to the external pressure, 10 the gripping members are released and may be fully retracted by means of upper and lower springs 31 contained within upper and lower sockets 32 provided in the upper and lower terminal portions 33, 34 of each gripping member and bearing against upper and lower stop or retainer rings 35 secured to the exterior of the intermediate body member 12 on opposite sides of the longitudinal slots 17 in any suitable manner, as through use of the upper and lower screws 36. Thus, it is apparent that the helical compression springs 31 are constantly urging the gripping members 18 to a retracted position out of engagement from the wall of the well casing, to correspondingly shift the rubber expansion sleeve 19 inwardly. However, this sleeve inherently tends to assume the inward position shown in Figs. 1 and 2. When a pressure differential of a sufficient magnitude to overcome the inherent elasticity of the rubber sleeve 19 and the force of the springs 31 is imposed within the tool, then the rubber sleeve 19 is expanded outwardly to correspondingly expand the gripping members 18 outwardly into anchoring engagement with the casing B. The higher the pressure differential within the tool, the greater will be the force holding the gripping members anchored to the well casing.

As described above, the gripping members 18 are released upon the relieving of the pressure internally of the tubing string C and tool A, or its substantially equalizing with respect to the external pressure. In the event that a mere relieving of the pressure internally of the tool cannot occur, then an equalizing valve 37 is embodied in the tubing anchor A, to make it possible for such pressures to be substantially equalized.

The tubular mandrel or inner member 10 has an outwardly directed flange 38 provided with external left-hand threads 39 meshing with companion internal left-hand threads 40 in the intermediate body member 12. The internal left-hand threads 40 may be the same set of threads as are threadedly engaged by the clamp nut 25 and the upper cap or lock ring 15. The mandrel flange 38 is of a much shorter length than the distance between the upper end of the clamp nut 25 and the lower end of the cap 15, permitting the mandrel 10 to move longitudinally in both directions upon its rotation within the body 11 to the extent limited by engagement of the upper flange shoulder 41 with the lower end of the cap 15, or of the lower flange shoulder 42 with the upper end of the clamp nut 25.

When the mandrel 10 is threaded downwardly of the body 11 and occupies the position shown in Figs. 1 and 3, its lower cylindrical valve head portion 43 is moved within a cylindrical seat 46 in the clamp nut 25 and nipple 22 into sealing engagement with a suitable seal ring 47 contained within a groove 48 formed collectively in the upper end of the nipple 22 and the lower end of the clamp nut 25. This seal 47 will sealingly engage the periphery of the valve head 45 and prevent fluid from passing around the exterior of the latter in both directions. It is molded on a metallic ring 60 and has upper and lower outer lip portions 61 engaging the base 48a of the groove 48 to prevent fluid leakage around the seal ring 47 in both directions. When the mandrel is in the lower position disclosed in Fig. 1, with the valve head 45 engaging the seal 47, fluid cannot pass between the interior and exterior of the tool through one or more side openings or parts 49 provided in the intermediate body member 12 above the clamp nut 25. However, upon rotating the tubular man-

drel 10 to the right or in a clockwise direction with respect to the body, the tubular mandrel is elevated, by virtue of the threaded connection 39, 40, to the extent limited by engagement of the upper flange shoulder 41 with the cap 15, which displaces the cylindrical valve head 45 above its companion seal 47, as disclosed in Fig. 2, which then opens the side ports 49 and allows the fluid to pass through these ports to equalize the pressure internally and externally of the tubing anchor.

It is to be noted that the lower ends 50 of the slots 17 are inclined to some extent in a downward and outward direction to engage companion inclined surfaces 51 on the lower ends of the gripping members 18. The upper ends 52 of the slots 17 are also inclined in an outward and downward direction, to engage correspondingly inclined surfaces 53 on the upper ends of the gripping members. The inclined surfaces 50, 51 at the lower ends of the slots 17 and gripping members 18 are utilized to assist in holding the gripping members in their outward anchored position against the well casing B, whereas the upper surfaces 52, 53 are of a retracting character, to facilitate release and retraction of the gripping members 18 with respect to the well casing B.

In the event the gripping members 18 have been expanded outwardly by the expansion sleeve 19 and an internal pressure differential is maintained within the tool, then the hydraulic forces may be acting on the body member 11 from below, or on some other equipment (not shown) secured to the body and tending to elevate the latter. Should this action tend to occur, then the lower expander surfaces 50 are brought upwardly into engagement with the companion surfaces 51 at the lower end of the gripping members 18 and exert a laterally outward component of force tending to hold the gripping members 18 anchored against the well casing B.

Conversely, should the pressure within the tool be released, or equalized with respect to the pressure externally of the tool, and the gripping members 18 still fail to retract, then a downward force can be imposed on the tubing string C and mandrel 10, which will be transmitted through the intermediate body member 12 and cause the upper retracting surfaces 52 to engage the companion surfaces 53 on the upper ends of the gripping members 18 to urge the latter in an inward direction.

Normally, the parts of the tool occupy the relative positions shown in Fig. 1, in which the equalizing valve 37 is closed and the gripping members 18 and expansion sleeve 19 are retracted. The tool A, usually connected to another tool or well packer therebelow, is lowered in the well casing B to the point at which it is to be anchored to the well casing. The fluid in the tubing string C and within the tool A may then be subjected to pressure, the tool therebelow (not shown) usually effecting a seal with the well casing and enabling a pressure to be built up within the tubing string C and the tubing anchor A. This fluid under pressure will pass through the nipple ports 24 and expand the expansion sleeve 19 outwardly, forcing the anchoring members 18 laterally outward in their slots 17 into anchoring engagement with the wall of the well casing B (Fig. 3). As the pressure differential increases, the greater is the anchoring force exerted in an outward direction upon the anchoring members 18. The wickers or teeth 18a on the anchoring members are designed to resist longitudinal displacement of the tool A in both an upward and a downward direction.

Whenever it is desired to release the tubing anchor A, it is merely necessary to relieve the pressure therewithin, which will allow the expansion sleeve 19 to retract inherently, and which will enable the retractor spring 31 to shift the gripping members 18 back to their retracted positions, such as shown in Fig. 1, which will then allow the tubing string C and the tool A to be moved longitudinally in the well casing in either an upward or downward direction. With the parts in the condition just re-

ferred to, the tool A can be elevated in the well casing B and removed completely from the well bore.

Should a pressure differential remain in the tubing string C and the tool A, the gripping members 18 will be held in their anchored position against the well casing, in the manner disclosed in Fig. 3. Under these conditions, the gripping members 18 will prevent rotation of the body 11 of the tool, whereupon the tubing string C and the tubular mandrel 10 may be rotated in a clockwise or right-hand direction, to thread the mandrel upwardly within the body 11 and lift the valve head 45 above its companion seal 47, such as shown in Fig. 2, opening the side ports 49 and allowing the pressure internally and externally of the tool to equalize, thereby effecting retraction of the packing sleeve 19 and the gripping members 18 from the well casing. The tubing anchor A may now be elevated or lowered in the well casing B.

In the event it is desired to again expand the gripping members 18 into anchoring engagement with the well casing, the mandrel 10 must be relowered, to place its valve head 45 in sealing engagement with the companion seal 47. Such relowering action will occur by suitably holding the body 11 against rotation to permit the tubing string C and mandrel 10 to be rotated in a counterclockwise direction, or to the left. Usually, the tool (not shown) connected to and disposed below the tubing anchor A has provisions for preventing its rotation, which will also forestall rotation of the body 11 of the tubing anchor, to which it is connected. Following the relowering of the mandrel 10 and closing of the side ports 49, a pressure differential can again be imparted to the fluid in the tubing string C and tool A to again expand the anchoring members 18 outwardly into firm gripping engagement with the wall of the well casing B.

The inventor claims:

1. In an apparatus to be anchored in a well casing disposed in a well bore: a body having circumferentially spaced slots therein; casing gripping members slidably laterally in said slots; a pliant, elastic sleeve within said body and gripping members sealingly engaging said body on opposite sides of said slots and expandible outwardly by fluid under pressure therewithin to shift said gripping members outwardly into engagement with the well casing; and a sleeve within said elastic sleeve fixedly and immovably secured to said body and having a port for directing fluid under pressure into the interior of said elastic sleeve, said sleeve secured to said body having means thereon engaging said elastic sleeve to prevent an end portion of said elastic sleeve from moving away from sealing engagement with said body.

2. In an apparatus to be anchored in a well casing disposed in a well bore: a body having circumferentially spaced slots therein; casing gripping members slidably laterally in said slots; a pliant, elastic sleeve within said body and gripping members sealingly engaging said body on opposite sides of said slots and expandible outwardly by fluid under pressure therewithin to shift said gripping members outwardly into engagement with the well casing, the lower ends of said slots and the lower ends of said gripping members being inclined in a downward and outward direction and engageable with each other upon upward movement of said body relative to said gripping members to urge the latter laterally outward.

3. In an apparatus to be anchored in a well casing disposed in a well bore: a body having circumferentially spaced slots therein; casing gripping members slidably laterally in said slots; a pliant, elastic sleeve within said body and gripping members sealingly engaging said body on opposite sides of said slots and expandible outwardly by fluid under pressure therewithin to shift said gripping members outwardly into engagement with the well casing, the lower ends of said slots and the lower ends of said gripping members being inclined in a downward and outward direction and engageable with each other upon upward movement of said body relative to said gripping

members to urge the latter laterally outward; and a sleeve within said elastic sleeve secured to said body and having a port for directing fluid under pressure into the interior of said elastic sleeve.

5. In an apparatus to be anchored in a well casing disposed in a well bore: a body having circumferentially spaced slots therein; casing gripping members slidably laterally in said slots; a pliant, elastic sleeve within said body and gripping members sealingly engaging said body on opposite sides of said slots and expandible outwardly by fluid under pressure therewithin to shift said gripping members outwardly into engagement with the well casing, the lower ends of said slots and the lower ends of said gripping members being inclined in a downward and outward direction and engageable with each other upon upward movement of said body relative to said gripping members to urge the latter laterally outward; the upper ends of said slots and the upper ends of said gripping members being inclined in a downward and outward direction and engageable with each other upon downward movement of said body relative to said gripping members to urge the latter laterally inward.

20 6. In an apparatus to be anchored in a well casing disposed in a well bore: a body having circumferentially spaced slots therein; casing gripping members slidably laterally in said slots; a pliant, elastic sleeve within said body and gripping members sealingly engaging said body on opposite sides of said slots and expandible outwardly by fluid under pressure therewithin to shift said gripping members outwardly into engagement with the well casing; the upper ends of said slots and the upper ends of said gripping members being inclined in a downward and outward direction and engageable with each other upon downward movement of said body relative to said gripping members to urge the latter laterally inward.

25 7. In an apparatus to be anchored in a well casing disposed in a well bore: a body having circumferentially spaced slots therein; casing gripping members slidably laterally in said slots; a pliant, elastic sleeve within said body and gripping members sealingly engaging said body on opposite sides of said slots and expandible outwardly by fluid under pressure therewithin to shift said gripping members outwardly into engagement with the well casing; a tubular mandrel connectible to a tubing string and telescoped within said body and movable longitudinally relative thereto, said body having a side port above said elastic sleeve; and valve means operable by said mandrel in response to manipulation of the tubing string and moving longitudinally of said body to selectively open or close said body side port.

40 8. In an apparatus to be anchored in a well casing disposed in a well bore: a body having circumferentially spaced slots therein; casing gripping members slidably laterally in said slots; a pliant, elastic sleeve within said body and gripping members sealingly engaging said body on opposite sides of said slots and expandible outwardly by fluid under pressure therewithin to shift said gripping members outwardly into engagement with the well casing; a tubular mandrel connectible to a tubing string and threaded within said body for movement longitudinally relative thereto, said body having a side port above said elastic sleeve; and valve means operable by said mandrel in response to rotation and longitudinal movement of said mandrel with respect to said body for selectively opening or closing said body side port.

45 9. In an apparatus to be anchored in a well casing disposed in a well bore: a body having circumferentially spaced slots therein; casing gripping members slidably laterally in said slots; a pliant, elastic sleeve within said body and gripping members sealingly engaging said body on opposite sides of said slots and expandible outwardly by fluid under pressure therewithin to shift said gripping members outwardly into engagement with the well casing; a tubular mandrel connectible to a tubing string and threaded within said body for movement longitudinally

relative thereto; said body having a side port; valve means operable by said mandrel in response to rotation and longitudinal movement of said mandrel with respect to said body for selectively opening or closing said body side port; and a sleeve within said elastic sleeve secured to said body and having a port for directing fluid under pressure into the interior of said elastic sleeve.

9. In an apparatus to be anchored in a well casing disposed in a well bore: a body having circumferentially spaced slots therein; casing gripping members slidable laterally in said slots; a pliant, elastic sleeve within said body and gripping members sealingly engaging said body on opposite sides of said slots and expandible outwardly by fluid under pressure therewithin to shift said gripping members outwardly into engagement with the well casing; a tubular mandrel connectible to a tubing string and threaded within said body for movement longitudinally relative thereto; said body having a side port; valve means operable by said mandrel in response to rotation and longitudinal movement of said mandrel with respect to said body for selectively opening or closing said body side port; the lower ends of said slots and the lower ends of said gripping members being inclined in a downward and outward direction and engageable with each other upon upward movement of said body relative to said gripping members to urge the latter laterally outward; and a sleeve within said elastic sleeve

20 secured to said body and having a port for directing fluid under pressure into the interior of said elastic sleeve.

10. In an apparatus to be anchored in a well casing disposed in a well bore: a body having circumferentially spaced slots therein; casing gripping members slidable laterally in said slots; a pliant, elastic sleeve within said body and gripping members sealingly engaging said body on opposite sides of said slots and expandible outwardly by fluid under pressure therewithin to shift said gripping members outwardly into engagement with the well casing; a sleeve within said elastic sleeve fixedly and immovably secured to said body and having a port for directing fluid under pressure into the interior of said elastic sleeve; a tubular mandrel connectible to a tubing string and telescoped within said body and movable longitudinally relative thereto; said body having a side port; and valve means operable by said mandrel and movable longitudinally of said body to selectively open and close said body side port.
